UNITED STATES PATENT OFFICE.

JOHN F. WILLIAMS, OF KANSAS CITY, MISSOURI, ASSIGNOR TO THE ECONOMY GAS LAMP COMPANY, OF SAME PLACE.

DESIGN FOR A LAMP-FIXTURE.

SPECIFICATION forming part of Design No. 30,769, dated May 16, 1899.

Application filed April 25, 1899. Serial No. 714,461. Term of patent 14 years.

To all whom it may concern:

Be it known that I, JOHN F. WILLIAMS, a citizen of the United States, residing at Kansas City, in the county of Jackson and State 5 of Missouri, have invented and produced a new and original Design for Lamp-Fixtures, of which the following is a specification.

My present invention relates to a new and original design for lamp-fixtures, of which the following is a specification, reference being had to the annexed drawing, wherein the fixture is shown in elevation.

The fixture consists of a curved arm or member A, carrying at its upper end a fitting or casting B, and extending up from said fitting is an arm C. A reservoir D is mounted on the upper end of said arm C, and a hook E extends from the reservoir, as shown. A fitting F is secured to the lower end of arm A, 15 and an arm G extends down therefrom, the lower end of the arm being bent or curved out

to one side forming a horizontal section H. A burner support or fitting I is secured to the end of said section H. An arm or member J, similar to arm G and having a horizontal section K corresponding to the section H, is secured to the opposite side of said burner support or fitting L. The upper end of said arm J carries a fitting L, and extending out from said fitting is an arm M. An arm N extends 25 out from fitting F toward arm M.

Having thus described my invention, what I claim is—

The design for a lamp-fixture herein shown and described.

In witness whereof I hereunto set my hand 35 in the presence of two witnesses.

JOHN F. WILLIAMS.
